UNITED STATES PATENT OFFICE.

WILLIAM C. MEYER, OF BEVERLY, MASSACHUSETTS, ASSIGNOR TO UNITED SHOE MACHINERY COMPANY, OF PATERSON, NEW JERSEY, A CORPORATION OF NEW JERSEY.

INSEAM SHOE-SEWING MACHINE.

1,160,935.

Specification of Letters Patent. Patented Nov. 16, 1915.

Original application filed June 22, 1910, Serial No. 568,248. Divided and this application filed July 24, 1912. Serial No. 711,226.

To all whom it may concern:

Be it known that I, WILLIAM C. MEYER, a citizen of the United States, residing at Beverly, in the county of Essex and Commonwealth of Massachusetts, have invented certain Improvements in Inseam Shoe-Sewing Machines, of which the following description, in connection with the accompanying drawings, is a specification, like reference characters on the drawings indicating like parts in the several figures.

The present invention relates to shoe sewing machines, and more particularly to welt guide mechanisms for such machines.

15 The object of the invention is to produce a shoe sewing machine having an improved welt guide mechanism which is simple and light in construction, which may be rapidly and accurately operated in timed relation 20 to the other parts of the machine with a minimum of friction.

With the above object in view the invention comprises certain improved features set forth in the following description and 25 particularly pointed out in the claims.

The various features of the invention will be clearly understood from an inspection of the accompanying drawings illustrating a machine embodying the same in their preferred forms.

30 Figure 1 of the drawings is a view in side elevation, partly in section, of the machine; Fig. 2 is a longitudinal sectional elevation of the machine; Fig. 3 is a detail sectional view taken on the line 3—3 of Fig. 2; and Fig. 4 is a detail, cross-sectional view taken on the line 4—4 of Fig. 3.

The machine illustrated in the drawings is a welt shoe sewing machine adapted to 40 sew the welt to the upper and insole of a lasted shoe. The principal parts of the machine are a curved hook needle entering the shoe from the outside so that the chain of the seam of stitches is laid on the welt; a 45 curved awl entering the channel of the shoe; a thread-arm, a looper, a takeup, an auxiliary takeup, a tension device, a channel guide and a welt guide. These parts have the same general mode of operation as the corresponding parts in the well-known Good-year welt and turn shoe sewing machine, the construction and mode of operation of which is disclosed with substantial accuracy

in the patent to French and Meyer, No. 412,704.

Referring to the drawings, 1 indicates the curved hook needle, 2 the awl, 3 the thread arm, 4 the looper, 5 the takeup, 6 the auxiliary takeup, 7 the channel guide, 8 the tension device.

The parts briefly referred to above are constructed and arranged in the same manner and operated by the same mechanism as the corresponding parts of the machine disclosed in Patent No. 1,059,380, dated April 22, 1913, the present application constituting a division of the application on which the said patent was granted. For a full and complete description of these parts, reference may be had to said patent.

The welt guide, indicated at 9, comprises the usual parts for supporting and guiding the welt. This guide is mounted upon the forward end of an arm 10 pivoted at 11 upon the forward end of the rod 12 which constitutes the welt guide controller bar. At its rear end the arm 10 is provided with a roll engaging a cam groove in a plate 13 secured to the frame of the machine, the shape of the groove being such that an oscillating movement is imparted to the arm 10 as the rod 12 is advanced and retracted. This oscillating movement of the arm 10 causes the portion of the welt guide in proximity to the needle to move in a path which practically coincides with the path of the needle so that the welt is always positioned with relation to the needle, regardless of the thickness of the work being operated upon.

The rod 12 is advanced and retracted to move the welt guide toward and from the shoe, and is locked in its advanced position during each cycle of operations of the machine by means of two springs 14 and 15, a cam actuated lever 16, two clutch boxes 17 and 18, and a clutch actuating block 19 pivotally mounted on the lower end of the lever 16. The clutch boxes 17 and 18, and the clutch actuating block 19, are all mounted upon the rod, and the rod is supported by means of a screw threaded pin 20 arranged axially of the pivotal connection between the clutch actuating block 19 and lever 16, and projecting into a slot in the rod. This construction is best shown in Figs. 2 and 4. The forward end of the rod

12 is pivotally supported at the upper end of an arm 21 pivotally mounted in a block 22 secured to the frame of the machine. The rod 12 is thus supported at two points, in a substantially frictionless manner, so that it responds quickly to its actuating mechanism, and can be moved with certainty into and out of engagement with the shoe at the proper times during each cycle of operations of the machine. The welt guide controller bar 12 is light, as compared with such bars or slides which have heretofore been used, and the manner in which it is mounted and actuated enables it to be operated in perfect timed relation to the other parts of the machine when the machine is running at high speed. To form a yielding stop for the welt guide controller bar, when no work is in the machine, a spring-pressed plunger 23 is mounted in the block 22 and is arranged to be engaged by an adjustable stop screw 24 mounted in the lower end of the arm 21. To enable the position of the welt guide to be adjusted with relation to the path of the needle the block 22 is mounted on the frame of the machine so as to be capable of vertical adjustment. The block is adjusted by means of a screw-threaded pin 25 (see Fig. 2) which is secured to the block 22 and which is engaged by an adjusting nut 26 seated in a slot in the machine frame. The block 22 is held in adjusted position by locking bolts 27 passed through slots 27^a in the block and screwed into a bracket 27^b on the frame. To advance the welt guide controller bar 12 so as to bring the welt guide 9 into engagement with the shoe, the springs 14 and 15 are utilized. Both of these springs act on the slide during the first portion of its advancing movement, but after the welt guide has nearly reached the shoe, the spring 15 is thrown out of operation, and the movement of the guide is continued by the spring 14. The spring 14 is light, as compared with the spring 15, and thus the final movement of the welt guide against the shoe is produced by a comparatively light pressure, and does not tend to disturb the shoe in the hands of the operator, or "knock it down" when the welt guide engages the shoe. To throw the spring 15 out of operation during the advancing movement of the rod 12, an adjustable eccentric pin 28 is provided which forms a stop for one side of the spring, as is clearly shown in Fig. 2.

The mechanism for locking the welt guide in its advanced position and for retracting the welt guide, comprises the clutch boxes 17 and 18 and the clutch actuating block 19. The clutch box 17 is provided with clutch rolls 29 which are arranged to be engaged by inclined surfaces or blocks 30 mounted in the clutch actuating block 19. These rolls rest against flat surfaces formed on the rod 12, and are forced against these surfaces to

clutch the rod and lock the rod in its advanced position when the block 19 is moved toward the left as viewed in Fig. 2. To cause the rolls to securely grip the rod and to avoid undue strain or breakage of the parts, the clutch box 17 is mounted so as to have a slight longitudinal movement with the rod. To this end the clutch box is provided with a peripheral groove 17^a which is engaged loosely by a projection 17^b from the frame of the machine. The clutch box is acted upon by a leaf spring 31 which tends to force the box toward the rear of the machine and hold it in the position indicated in Fig. 2. When the clutch box is actuated by the block 19 to grip the rod 12, it can move forward a short distance and thus insure accuracy in the operation of the clutch rolls and avoid breakage of any of the parts. This forward movement of the clutch box 17 also imparts a slight positive forward movement to the welt guide which gives a final positive squeeze to the work just before the welt guide is locked. The clutch box 18 is utilized in retracting the welt guide. This clutch box is provided with clutch rolls arranged in the same manner as the clutch rolls 29 of the box 17, and adapted to be engaged by the inclined surfaces of blocks 32 mounted in the opposite end of the block 19 from the blocks 30. The clutch box 18 is mounted to move longitudinally of the rod 12, and its forward movement is limited by the engagement of a shoulder 33 on the box with a projection on the machine frame. The clutch box 18 is connected with the clutch actuating block 19 so that it advances therewith, by a spring 34.

The nature and object of the invention having been explained, and the preferred embodiment of the invention having been described, what is claimed is:—

1. A shoe sewing machine, having, in combination, stitch forming devices including a curved hook needle, a welt guide, a welt guide controller bar, a pivotally mounted link supporting the bar at one point, and a cam lever for actuating the bar supporting the bar at another point.

2. A shoe sewing machine, having, in combination, stitch forming devices including a curved hook needle, a welt guide, a welt guide controller bar, a cam actuated lever, and means operated by the lever to lock the bar in advanced position and to retract the bar.

3. A shoe sewing machine, having, in combination, stitch forming devices including a curved hook needle, a welt guide, a welt guide controller bar, two springs for advancing the bar, and means for throwing one spring out of operation during the advancing movement of the bar.

4. A shoe sewing machine, having, in combination, stitch forming devices in-

- cluding a curved hook needle, a welt guide, a welt guide controller bar, a locking clutch box and an actuating clutch box mounted thereon, a clutch actuator mounted on the 5 bar between the boxes, arranged to coöperate with one box to lock the bar in advanced position and to coöperate with the other box to retract the bar, and means for moving the actuator.
10. 5. A shoe sewing machine, having, in combination, stitch forming devices including a curved hook needle, a welt guide, a spring to force the welt guide yieldingly into engagement with the work, means for 15 thereafter forcing the guide positively against the work and locking it in position, and means for retracting the welt guide during each cycle of operations of the machine.
20. 6. A shoe sewing machine, having, in combination, stitch forming devices including a curved hook needle, a welt guide, a welt guide controller bar, means for yieldingly forcing the bar toward the work 25 to bring the welt guide into engagement with the work, and means for gripping the bar and forcing it forward to force the welt guide against the work and for locking the bar in position.
30. 7. A shoe sewing machine, having, in combination, stitch forming devices including a curved hook needle, a welt guide, a welt guide controller bar, means for yieldingly forcing the welt guide bar toward the 35 work, a clutch box mounted on the bar, and movable therewith, and means for thereafter moving the clutch box to grip the bar and lock it in position.
8. A shoe sewing machine, having, in 40 combination, stitch forming devices including a curved hook needle, a welt guide, a welt guide controller bar, movable toward and from the shoe, a pivotally mounted arm supporting the forward end of the bar, and 45 a yielding stop for the arm to limit the forward movement of the bar.
9. A shoe sewing machine, having, in combination, stitch forming devices including a curved hook needle, a welt guide, a
- welt guide controller bar, a pivotally mounted arm supporting the forward end of the bar, and means for adjusting the arm to adjust the position of the welt guide. 50
10. A shoe sewing machine, having, in combination, stitch forming devices including a curved hook needle, a welt guide, a welt guide controller bar, a welt guide carrier pivotally mounted on the forward end of the bar, a stationary cam engaging the 55 welt carrier to impart an oscillating movement thereto during the movements of the bar, a pivotally mounted arm supporting the forward end of the bar, and means for adjusting the arm to adjust the position of 60 the welt guide carrier.
11. A shoe sewing machine, having, in combination, stitch forming devices, including a curved hook needle, a welt guide, a welt guide controller bar, clutch devices arranged to act on the bar, a clutch actuator 70 movable longitudinally of the bar and acting when moved in either direction to cause the clutch devices to clutch the bar.
12. A shoe sewing machine, having, in combination, stitch forming devices, including a curved hook needle, a welt guide, a welt guide controller bar, clutch devices mounted on the bar, a clutch actuator mounted on the bar for movement longitudinally thereof and acting when moved 75 in either direction to cause the clutch devices to clutch the bar.
13. A shoe sewing machine, having, in combination, stitch forming devices including a curved hook needle, a welt guide, a welt guide controller bar, a spring for yieldingly engaging the welt guide with the work, and a friction clutch for gripping 80 and moving the bar to advance the welt guide positively a predetermined distance. 85
